STRAIGHTENING MACHINE

Filed Aug. 3, 1931

UNITED STATES PATENT OFFICE

RALPH C. STIEFEL, OF ELLWOOD CITY, PENNSYLVANIA

STRAIGHTENING MACHINE

Application filed August 3, 1931. Serial No. 554,841.

The invention relates to machines for straightening round metal stock, such as tubes, rods, shafts, and the like, the object being to provide a machine for this purpose which is simple in construction, and hence economical to manufacture and operate, and which effectively removes short kinks as well as large bends from round stock.

The invention is illustrated in the accompanying drawings of which Fig. 1 is a somewhat diagrammatic plan view of a set of rolls forming the essential parts of the machine, with a tube in the line of pass through the rolls; Fig. 2 a side view of the machine with the near roll removed to show the straightening action of the machine; and Fig. 3 an end view of the machine.

The straightening machine provided according to this invention comprises a set of three rotatable cross-rolls mounted in a suitable frame or housing, each of the rolls being adapted to be driven. The rolls are so mounted that their axes are inclined to each other and to a pass line lying centrally of the rolls, which are adjustable radially of the pass line for straightening round stock of different diameters, and which may also have the inclination of their axes adjusted for the same purpose. The faces of two of the rolls are concave between their ends to form a pocket for receiving stock which is deflected progressively by an annular projection formed on the central portion of the third roll. Both ends of all three rolls are provided with annular projections which collectively form at each end of the rolls three-point stock-engaging faces spaced equidistant from the central pass line for holding the stock firmly in the pass line at each end of the pocket formed by the concavities in the faces of the two first-mentioned rolls.

Having reference to the illustrative embodiment of the invention, a set of three rolls 1, 2 and 3 is shown grouped around a central pass line 4, which is the axis of a tube 5 illustrated as being subjected to the straightening action of the rolls. As illustrated, the rolls are provided with suitable journals 6, 7 and 8 adapted to be mounted in suitable

adjustable bearings, and by which each of

the rolls may be driven on their respective axes which are inclined to each other and to pass line 4. The faces of rolls 1 and 2 are provided with curved concavities 9 and 10, respectively, and the mid-portion of the face of roll 3 is provided with a curved annular projection 11, which, in the throat or center 12 of the pass, is opposite to the deepest portions of concavities 9 and 10.

Adjacent to their ends, concave rolls 1 and 2 are provided with longitudinally-curved stock-engaging annular faces 15 and 16, respectively, the preferred extent of which, as measured along pass line 4, is indicated by the dimension lines A in Fig. 2. In a similar manner, roll 3 has its end portions provided with curved stock-engaging projections 17 indicated in Fig. 2 as being of the same extent as the corresponding projections 15 and 16 of the concave rolls. By suitably adjusting the axes of the several rolls, these extended end projections afford substantial line engagements of round stock on each side of the pocket formed by the concave rolls, and at each end of the pass. Thus, as shown in Fig. 3, there are extended three-point supports for a tube 5, each point of support being equidistant from the axis of the tube, which, as stated, normally lies in the pass line.

In the operation of the machine, the rolls are driven to feed round stock spirally on its axis and along the pass line of the machine. The medial annular projection 11 of roll 3 is of such height with relation to the stock-engaging end portions 15, 16 and 17 of the rolls that projection 11 progressively deflects a straight tube up to, or substantially to, its elastic limit, the pocket formed by the concavities 9 and 10 of rolls 1 and 2 being of such depth as to receive this amount of deflection of the stock. As to such portions of round stock as have no kinks or bends, the stock is merely progressively deflected and comes out of the machine in its original straight form. Where kinks or bends occur the deflection of the stock is beyond its elastic limit, so that the kinked or bent portions emerge straight.

In the operation of this straightening ma- 100.

chine, I have found that by firmly engaging stock at relatively close intervals by the end portions of three cross-rolls, and by progressively deflecting the stock by a projection 5 formed on one of the rolls into a relatively short pocket formed by concavities on the other rolls, short kinks and large bends may be effectively and quickly removed from round stock. The machine being simple in 10 construction, it is economical to manufacture and operate.

According to the provisions of the patent 15 statutes I have explained the principle and operation of my invention, and have illustrated and described what I now consider to represent its best embodiment. However, I desire to have it understood, within the scope 20 of the appended claims, the invention may be practiced otherwise than as illustrated and described.

I claim:

1. A machine for straightening round stock, comprising a set of three rotatable cross-rolls having their axes inclined to each 25 other and to a central pass line, the faces of two of the rolls being concave between their ends to form a pocket for receiving progressively deflected stock, the mid-portion of the third roll having its face provided with an 30 annular projection for progressively deflecting stock into said pocket, and the ends of the three rolls being provided with annular projections collectively forming at both ends of the rolls three-point stock-engaging faces 35 spaced equidistant from said central pass line to hold the stock firmly in said pass line at each end of said pocket.

2. A machine for straightening round stock, comprising a set of three rotatable 40 cross-rolls having their axes inclined to each other and to a central pass line, the faces of two of the rolls being concave between their ends to form a pocket for receiving progressively deflected stock, the mid-portion of the 45 third roll having its face provided with an annular projection for progressively deflecting stock into said pocket, and the ends of the three rolls being provided with extended annular and longitudinally curved projections collectively forming at both ends of the 50 rolls three-point stock-engaging faces spaced equidistant from said central pass line to hold the stock firmly in said pass line at each end of said pocket.

55 In testimony whereof, I sign my name.
RALPH C. STIEFEL.
